UNITED STATES PATENT OFFICE

SAMUEL J. KAZ, OF CHICAGO, ILLINOIS, ASSIGNOR TO MOHAWK PRODUCTS COMPANY,
OF CHICAGO, ILLINOIS, A CORPORATION OF ILLINOIS

DESIGN FOR A TABLE LAMP

Application filed September 30, 1930. Serial No. 37,096. Term of patent 7 years.

To all whom it may concern:

Be it known that I, SAMUEL J. KAZ, a citizen of the United States, residing at Chicago, in the county of Cook and State of Illinois, have invented a new, original, and ornamental Design for a Table Lamp, of which the following is a specification, reference being had to the accompanying drawing, forming part thereof.

In the drawing,—

Fig. 1 is a front elevational view of a table lamp embodying my new design; and

Fig. 2 is a perspective view of the same.

In my new design the lacing at the top and bottom edges of the shade extend entirely around the shade. The decorative band near the foot of the base also extends entirely therearound. The design of flowers and leaves shown in the drawings appears only on one side of the shade and the base, the opposite side of the shade and base being plain.

I claim:

The ornamental design for a table lamp substantially as shown and described.

SAMUEL J. KAZ.
